(57) **CLAIM**

The ornamental design for portion of an electrical dimmer switch and cover plate, as shown and described.

DESCRIPTION

FIG. 1 is a front, bottom and right side perspective view of the design;

FIG. 2 is a front view thereof;

FIG. 3 is a right side view thereof;

FIG. 4 is a left side view thereof;

FIG. 5 is a top plan view thereof; and,

FIG. 6 is a bottom plan view thereof.

The back forms no part of the design. The broken line showing in the drawings is illustrative and forms no part of the claimed design.
